UNITED STATES PATENT OFFICE

95,459

DESIGN FOR A COMBINED STANDARD AND BASE FOR FLOOR LAMPS

Eugene Schwarz, Alexandria, Ind., assignor to
The Mantle Lamp Company of America, Chi-
cago, Ill., a corporation of Illinois

Application February 15, 1935, Serial No. 55,449

Term of patent 7 years

To all whom it may concern:

Be it known that I, Eugene Schwarz, a citizen of the United States of America, residing at Alexandria, in the county of Madison and State of Indiana, have invented a new, original, and ornamental Design for a Combined Standard and Base for Floor Lamps, of which the following is a specification, reference being had to the accompanying drawing, forming a part thereof:

Figure 1 is a view in elevation of a combined

standard and base for floor lamps, showing my new design.

Figure 2 is a view taken on the line 2—2 of Figure 1, showing the design of the combined standard and base for floor lamps.

I claim:

The ornamental design for a combined standard and base for floor lamps, as shown.

In testimony whereof I affix my signature.

EUGENE SCHWARZ.
